UNITED STATES PATENT OFFICE.

JOSEPH C. FOWLER, OF WASHINGTON, DISTRICT OF COLUMBIA, ASSIGNOR
OF ONE-HALF TO L. G. HINE, OF SAME PLACE.

MACHINE FOR PRODUCING TYPE-BARS.

SPECIFICATION forming part of Letters Patent No. 481,920, dated August 30, 1892.

Application filed April 15, 1892. Serial No. 429,286. (No model.)

To all whom it may concern:

Be it known that I, JOSEPH C. FOWLER, a citizen of the United States, residing at Washington, in the District of Columbia, have invented new and useful Improvements in Machines for Producing Type-Bars, of which the following is a specification.

My invention relates to that class of mechanism used for setting up a series of matrices in orderly arrangement and in such manner that they may form part of a mold in which a line or some part thereof may be cast in a single piece having an intelligible arrangement of type characters corresponding with those of the matrices, the line when removed from the mold being in condition to be set up with others and locked up in a proof-galley or other device, where one or more impressions may be made in any suitable form of press.

My invention relates more particularly to that class of this mechanism commonly known as the "Mergenthaler linotype-machines." Broadly speaking, these machines are now substantially automatic, the matrix selection being effected by a keyboard, the matrices assembled, their position rectified, the line or series expanded, the mold formed, the matrices locked up, the cast made, and the series of matrices being carried upward, delivered to a distributing-bar, and thence returned to their proper cells in the magazine.

While this machine has given excellent results, it has been regarded as desirable that the mechanism be simplified to such a degree as to render a higher speed attainable, both in assembling the matrices and in their distribution to the magazine.

It is my purpose to provide simple means whereby the operations of locking up and clamping the line of matrices in the mold, casting the line of type, and finally separating the mold and distributing the matrices may all proceed in their proper order or succession at the same time that the selection of matrices by the keyboard is carried on, together with their delivery to the assembling space, whereby at the completion of each line selection the matrices selected are arranged in an orderly manner in the assembly-space ready to be justified, clamped, and locked up in the mold the preceding line is justified and

locked up, and a third line of matrices is advanced to the mold, locked up, the cast made, the mold opened, or the cast line of type ejected by suitable means, and the line thus formed delivered. This series of operations is practically synchronous, for although they do not take place at the same absolute instant they are completed in the same period of time, said operation being divided into three separate series and each series being directed to three separate points upon the machine-table, the concurrence of the three separate series of mechanical operations into which the action of the mechanism is divided being the means whereby I am enabled to slow up the movement of the machine as a whole and to accomplish the final results sought with less wear and tear and with a better average speed than has usually been practicable.

It is another purpose of my invention to provide means whereby the individual matrices are driven singly and in rapid succession from the assembling-space and taken to the distribution-bar by carriers having continuous movement—such, for example, as flexible belts or chains, between which the matrices are successively received as they are taken from the assembling-space. This part of my invention also comprises the combination, with the matrix-elevating apparatus referred to, of means whereby the flexible continuously-traveling devices by which the matrices are taken to the distribution-bar shall follow a curved path or caused to follow such a path that the matrices contained in the assembly-space shall turn upon their longitudinal centers in order to present their matrix edges in proper position for the next selection.

It is my further purpose to provide a machine of this character in which an element shall be a machine table or platform having intermittent rotation through an arc of ninety degrees, or about one-fourth part of a complete revolution, the sides of said table or platform being each provided with an assembling space or chamber, a pusher to advance the gathered matrices and to act as a clamp when the mold is locked up, a spring-pressed riser or head to support the gathered type against the action of the pusher, and a driver to carry the matrices out of the assembling

space or chamber and carry each in its order and into the carriers, by which it is taken to the distribution-bar, and suitable means for giving an intermittent fractional revolution 5 to the machine-table at suitable intervals, as determined by the operator.

It is my purpose, also, to provide and combine with the rotating machine table or platform, equipped substantially as described, 10 means whereby its fractional revolution may be initiated by the operator and automatically arrested by the action of the mechanism and locked or held in position, subject, however, to such limited play as may be required 15 for the justification of the table in order to make a close joint with the mold from end to end of the latter.

It is my further purpose to combine with a machine of the type specified a machine table 20 or platform having a polygonal form, the straight edges thereof being of substantially equal length and each provided with duplicate means suitable for the assemblage, justification, and locking up of a line of matrices, and provided, also, with means for driving said matrices out of the assembling-space singly and successively to enable them to be carried to the distribution mechanism.

I purpose, also, to provide a machine of 30 this kind with a machine-table provided along its margin with a series of duplicate spaces for assembling and holding the matrices, said table being mounted upon a central axis and receiving intermittent fractional rotation at 35 the will of the operator to advance the series of duplicate spaces one step, bringing each in position to enable further operation to be performed thereon in the same or substantially the same time that preceding and succeeding 40 steps are performed with relation to the remaining spaces of the series.

I also purpose providing machines of this character with a machine table or platform combined with means for giving intermittent 45 fractional rotation thereto at the will of the operator, a bank of keys by which the magazine-cells are opened and a single matrix dropped by the operation of any one key, means for carrying the matrices to and assembling them in one of a series of marginal 50 assembling-spaces on the machine-table, means for locking up the matrices so assembled and casting a line of type therefrom when the assembling space or chamber has 55 been advanced by a fractional rotary movement of the table, by which a second assembling-space is brought into position for receiving the selected matrices for a second line, and means for separating and distributing 60 the matrices from which the cast is made when the table has been advanced by a second fractional movement on its axis, thereby also bringing the second line assembled into position for casting and advancing a third 65 assembling-space to the point where it receives the assembling-matrices, thereby enabling the several operations of assembling,

casting, and distributing to be carried on simultaneously, or practically so, at a plurality of different points on the same table.

My invention comprises simple automatic means for engaging the separately-elevated matrices with the distribution-bar, for preventing the passage upon the bar of one matrix until the preceding matrix has been carried forward thereon by the proper advancing device, and means whereby the assembled line is justified at one point in the intermittent movement of the machine-table and locked up under the proper line compression 80 at a succeeding point in the movement of the table where the casting is accomplished, and finally the distribution of the matrices at a third point in the rotary intermittent movement, the mechanical action at each of the 85 three points being carried on simultaneously.

My invention also contemplates the material simplification of the structure and organization of these machines, a material improvement in their operation by reason of increased 90 expedition, diminished wear and tear of the parts, an avoidance of the necessity for extreme micrometric accuracy in the contacting-surfaces, which is always one result of a complicated organization of a large number of 95 mechanical elements, and a material improvement in the economies of time, speed, and power, whereby I am able to attain the final results sought in the same period of time now required by other systems, but at a less speed 100 of the mechanism, or at an equal speed, but in a less period of time.

My invention consists, to the several purposes specified, in the novel features of construction and new combinations of parts hereinafter fully explained, and then particularly pointed out and defined in the claims, with which this specification concludes.

To enable others skilled in the art to which my said invention appertains to understand 110 and to make, construct, and use the same, I will proceed to describe in detail a machine in which my invention is embodied, reference being had for such purposes to the drawings accompanying this specification, in which— 115

Figure 1 is a front elevation of a part of a machine embodying my invention, showing the magazine, the distributing mechanism, and keyboard, with the assembling devices. Fig. 1^a is a detail perspective view showing 120 the leaf-spring at the lower end of the magazine. Fig. 2 is a sectional elevation taken from the left-hand end of the machine, the table and its actuating devices being in dotted lines. Fig. 3 is a plan view, on an enlarged 125 scale, of the machine-table. Fig. 3^a is a view of one of the matrices used in said machine. Fig. 3^b is a detail perspective view of the plate, having beveled side arms, between which the matrix entrance and exit openings are located. Fig. 4 is a side or edge elevation of the machine-table as shown in Fig. 3. Fig. 4^a is a vertical longitudinal section in the line of one of the assembling-spaces on the table,

showing the matrix assembling and setting mechanism at work. Fig. 5 is a similar view showing the line of matrices set up in an assembling-space and locked up in position for casting. Fig. 6 is a vertical section of the machine, taken through the center of the machine-table and through the mold and crucible. Fig. 7 is a vertical section of an assembling-space in the machine-table, showing the matrix ejecting and distributing devices in operation. Fig. 8 is a plan view of the lower portion of the mechanism in Fig. 7. Fig. 8^a is an end elevation, on an enlarged scale, of the devices shown in Fig. 8. Fig. 9 is a plan view of the mold and a part of the crucible. Fig. 10 is a section of the same upon the line 10-10, Fig. 9, showing a portion of the rotary table and a matrix in position therein for casting. Fig. 11 is a detail perspective view of the upper jaw of the mold. Fig. 12 is a detail perspective of the lower jaw of the same. Fig. 13 is a face elevation of one of the supporting-brackets between which the mold lies. Fig. 14 is a perspective of a line 25 of type cast in said mold. Fig. 15 is a rear elevation of the crucible and its supports. Fig. 16 is a vertical section showing the matrix-ejecting mechanism and illustrating a modified form of the means for withdrawing 30 the matrices which have been partly ejected from the assembling-space or which are of less than usual length. Fig. 17 is a detail front elevation of the devices by which the matrices are placed upon the distribution-bar. Fig. 18 is an end elevation of the devices 35 whereby the crowding of the matrices on the distribution-bar is prevented. Fig. 19 is a plan view of part of the devices shown in Fig. 17. Fig. 20 is a detail view of part of 40 the apparatus shown in Fig. 18. Fig. 21 is a detail perspective of the guard shown in Fig. 18. Fig. 22 is a detail view of one of the flexible carriers for the distribution mechanism, showing the means for twisting the same. 45 Figs. 22^a, 22^b, and 22^c are views showing the construction of parts of the flexible carriers. Fig. 23 is an end elevation of the lower part 50 of the machine, showing the starting mechanism and the cams by which the automatic action is governed. Fig. 24 is a horizontal section of Fig. 23, taken just below the cams on the shaft of the table. Fig. 25 is a front elevation of part of the devices shown in Fig. 24. Fig. 26 is a vertical section 55 of the ejecting mechanism. Fig. 27 is a bottom plan view of the parts shown in Fig. 26. Fig. 28 is a plan view of the index disk or cam. Fig. 29 is a central vertical section of the same. Fig. 30 is a perspective view of 60 the latch. Fig. 31 is a plan view of the latch-cam. Fig. 32 is a central vertical section of the same. Fig. 33 is a plan view of the stop-cam. Fig. 34 is a vertical section of the parts shown in Fig. 33. Fig. 35 is a plan view of 65 the lock-up cam. Fig. 36 is a central section of the cam shown in Fig. 35. Fig. 37 is a dia-grammatical plan view, partly in section, for

the purpose of indicating the relative position of the keyboard, rotary table, and crucible. Fig. 38 is a detail sectional elevation to 70 more clearly show the mechanism for intermittently rotating the table. Fig. 39 is a detail perspective view to more clearly show the devices for preventing crowding of the matrices on the distribution-bar, and Fig. 40 is a 75 detail perspective view of the lining-head and its supports. Fig. 41 is a diagram to illustrate the relations of the follow-block to the driving-arm and to indicate the manner in which the depending end of said follow-block 80 is caused to engage the driving-arm as the matrices are brought into position for distribution.

I shall have occasion to direct attention hereinafter to those features which mark the 85 difference between my invention and the prior art; but I may state at the outset that there are several matters of paramount importance and value which I will particularize at this point merely by reason of their prominence 90 in novelty and value and their relative importance in function.

One of the features referred to comprises the machine table or platform mounted upon a central axis and combined with suitable 95 means whereby it may have intermittent fractional rotation on its axis at the will of the operator. This table may be polygonal in form, and there is no imperative limitation as to the number of sides, as I may construct 100 it in the form of a triangle, a quadrilateral, a pentagon, a hexagon, or any other regular polygon. For reasons which will appear in the course of this description I prefer that said table be square, or practically so, and mounted on a shaft the axis of which is substantially coincident with the point of intersection of the diagonals of the square. Upon each of its four sides the table is provided with suitable assembling-spaces for receiving 105 and retaining the selected matrices, the assembling-spaces upon any one of the four sides being substantial duplicates of the other three. In its first position the assembling-space on one of the sides receives the 110 selected matrices taken from the magazine by the operation of the keys. The completed line is justified and the matrices are locked up in the mold, the casting is accomplished, and the matrices are then removed from the 115 assembling-space in which they were first received and taken direct to the distribution-bar to be returned to the magazine. These 120 several successive steps and the minor operations attending them are all performed without removing the matrices from the assembling-space where they were first placed and without removing the same from the table of 125 which it forms a permanent portion. The only change in this respect is the change of 130 location produced by the intermittent fractional revolution of the machine-table, by which the assembling-space in which a line of matrices has been placed is advanced by

a rotary movement of the machine-table of such extent as to bring the next succeeding assembling-space into the place just vacated by the one in which the matrices have assembled. The latter is brought into position to be locked up and form part of the mold in which the type-line is cast while the second assembling-space is receiving a second line of matrices. A further movement of the table carries the assembling-space and the matrices from which the cast has just been made to a third point, bringing a third assembling-space into the place vacated by the second, where it receives a third line of matrices during the period of time in which the second assembling-space is used in the mold. During this same period the matrices in the first assembling-space from which a type-line has been cast are in process of distribution. It will be seen that the three different steps are not only carried forward simultaneously at the three different points of arrest in the fractional revolution of the table, but that the three successive steps of assembling, casting, and distributing are executed in connection with one and the same assembling-space in its three successive positions, the matrices suffering no removal therefrom until they are taken to the distribution-bar. As the steps referred to are three in number, the fourth side of the square table, although provided with an assembling-space like the others, may be regarded, nevertheless, as an idler. The reasons for preferring the form of table shown will be fully explained hereinafter. It will be seen that the three distinct operations of assembling, casting, and distributing, with the minor operations attending each step, are practically synchronous, and the periods of time between which the machine-table is advanced are measured by the time required by the operator in selecting and assembling the matrices in the assembling-space which lies in position to receive them. Mechanical operations are, as a rule, performed automatically in less time than the same work can be performed manually, and this is practically the case in the present instance. It follows, therefore, that the mechanism can be operated as rapidly as the keys can strike to open the cells of the magazine and release the matrices, the speed, therefore, being limited by the rapidity, skill, and accuracy of the operator.

Another salient feature of my invention comprises the method of distribution of the matrices, which consists in taking them by means of continuously-moving flexible carriers as they are ejected from the assembling space or chamber direct to the distribution-bar, whence they are delivered to the proper cells of the magazine. This portion of my invention also comprises, in addition to the foregoing, the provision of means of extremely simple character whereby the matrices are automatically placed in their proper order upon the distribution-bar and whereby a proper in-

terval is preserved between them to enable the matrix-carriers to engage the matrices separately and maintain a suitable space between them. This portion of my invention also includes, but as a separate feature, means whereby the matrices may be taken from the assembling-space in succession or individually and carried to the point of delivery to the distribution-bar, the means whereby they are removed from the assembling-space being so modified and improved as to be independent of the length of the matrix-plate should the latter be shortened for any reason.

Finally my invention comprises simple means whereby longitudinal ribs shall be formed upon the flat vertical face of the body portion of the type-line, said ribs having substantial parallelism with the top and bottom of said body portion and being preferably removed by a narrow space from the upper and lower edges. The outer faces of these ribs, which are in low relief, are formed in the mold with such accuracy that they contact with the rear face of the type-line in front and not only render the two lines accurately parallel, but afford support and contact throughout the entire series of type-lines, holding each in its place and preventing displacement or dropping out of the type should the form or galley chance to be inverted.

In describing the operative parts of the machine I will follow as closely as may be the order in which the several parts act, this being the natural order.

Referring to the drawings, the reference numeral 1, Fig. 3^a, indicates the ordinary and well-known form of matrix used in machines of this character, its parts and the manner of using the same being so well known to those skilled in the art as to require no specific description. These matrices are stored in the cells 2, Fig. 1, of a magazine, which will be of a known construction or of any other preferred form. The magazine is supported upon the upper extension 3 of the machine-frame 4, Fig. 2, where it is preferably inclosed between two parallel walls 5, a transparent pane 6 affording a complete view of the same. The individual cells 7 of the magazine I arrange in such manner that they converge from their upper to their lower extremities at a small angle, thereby bringing the discharge-openings closely adjacent to each other, while the receiving-openings above are separated from each other by short but regular intervals to facilitate the distribution of the matrices. The magazine-cell of greatest length and containing the greatest number of matrices is the vertical cell 7^a, dividing the magazine centrally into two substantially similar parts. The lower or discharge ends of the cells in each half are cut upon a line inclining laterally and upward, thereby causing the lower end of the magazine to approximate a V shape. The matrices lie in these cells end to end, as usual, their edges being presented to the front of the machine, those

edges having characters formed therein or thereon being all turned the same way.

Directly beneath and parallel with the V-shaped lower end of the magazine, separated 5 from the discharge ends of the cells, are two independent flat belts 8 and 9, carried in unison by pulleys 10 at the sides of the magazine and meeting below and a little to one side of the discharge end of the central cell 10 7^a. At this point both belts come upon a pulley 12, the belt 9 overlying and running upon and in unison with the belt 8. In the same relative position both belts pass to a pulley 13, and passing over the same they run downward to guide-rolls 14, having their axes in substantially the same horizontal plane, and so located as to bring their surfaces near the face of the machine-table, Figs. 1 and 2. The axes of all the pulleys mentioned are parallel with a 15 horizontal line drawn from front to rear of the machine, and the arrangement is such that the two belts 8 and 9 as they pass from the pulleys 10 to the pulley 12 travel directly beneath the exit ends or discharge ends of the 20 cells of the magazine at such distance therefrom and at such speed that the matrices released and allowed to drop from the cells by gravity will easily be taken and carried onward in their proper relative position. To 25 prevent the remote chance of any one of said matrices becoming so far displaced that one end is thrown upward on the belt 8 as it passes over the face of the pulley 12, whereby said matrix may be caused to assume a position transverse to the belts 8 and 9, I mount upon the apex or lowest point of the magazine-cells a delicate leaf-spring 10^a, Figs. 1 and 1^a, which hangs downward, so that its point is but little above the surface of the 30 belt 9, where it will touch the upper surfaces of the matrices passing upon the belt or be in very close proximity to them. Being of extremely delicate tension and highly elastic it offers no obstacle to their passage and can 35 cause no displacement, but on the contrary prevents the displacement referred to above. Upon reaching the pulley 12 they pass, still retaining the same relative position, into the grasp of the two belts 8 and 9 and remain 40 therein until they have emerged below the guide-rolls 14. It will readily be understood from the figures referred to that the matrices drop upon the belts 8 and 9 lengthwise and retain this position while in engagement with 45 said belts, their matrix edges or those having characters formed therein or thereon being turned toward the front of the machine.

The machine table or platform 15, Fig. 2, to which reference has already been made, is 50 preferably square, Fig. 3, its sides being of a length somewhat greater than the maximum length of a type-line. It is mounted upon a vertical shaft 16, Fig. 6, having its axis coincident with the point of intersection of the 55 diagonals of the square, or substantially so. The method of imparting movement to this shaft will be explained hereinafter, my pres-

ent purpose being simply to point out the constructive features and the relative location of the mechanical parts. The shaft 16 is 7^c stepped in a bearing upon the base-plate of the machine, or it may be supported in any other manner familiar to machinists.

Upon each of its four sides the table 15 is provided with an assembling-space 17, Figs. 7^c 3 and 4, into which the selected matrices released from the magazine-cells pass as they emerge from the grasp of the belts 8 and 9 below the guide-rolls 14. The table being quadrilateral and the four assembling-spaces 8^c being in all material respects duplicates one of another, a description of one will be sufficient for all. Each assembling-space 17 is located quite near the edge of the table and parallel therewith, as seen most clearly in Fig. 8^c 3. It consists of a chamber, space, or recess, (denoted by said reference-numeral 17,) said chamber lying below the upper surface of the table, Figs. 4 and 5, which is removed to leave nearly the whole length of said chamber open 9^c at the top. The width of this opening is about equal to the width of the matrices 1 (see Fig. 3^a) at their middle portions, or between the projecting lips 19 at one end and the similar lips 20 at the other end. These lips project 95 over the sides of the chamber 17 and their adjacent shoulders rest upon the surface of the table and beneath longitudinal shoulders 21, Figs. 10 and 26, a little above the bottom of the chamber 17. In the assembling-space 100 the matrices stand erect, with their width transverse to the longitudinal line of the chamber 17, and to enable them to enter said chamber in this position an entrance is provided by widening the opening at or near one 105 end of said chamber to form an entrance-opening 22, Fig. 3, of a trifle more than the actual width required.

Upon the table, at the rear end of the assembling-chamber, is mounted a plate 23, Figs. 110 3, 3^b, 4, and 5, which extends across the opening in the table and is provided with side arms 24, their inner adjacent faces 25 being beveled to have a slight convergence downward, as shown in Fig. 3^a. The exit-opening 115 22^a, Fig. 3, is comprised between the transverse shoulders 26, forming part of the plate 23, as shown in Fig. 3^b, and two opposite lugs 27, parallel with said shoulders and mounted upon the side arms 24. The area of the entrance-opening is greater than that absolutely required by the thickness of the matrix-entering, as a special accuracy in this respect is unnecessary. As the matrix emerges from 120 between the belts 8 and 9 and passes below the guide-rolls 14 its lower end passes into the entrance-opening 22, Fig. 4^a, and enters the assembling space or chamber 17. Within the rearward end of the latter, beneath the plate 23, is a pusher and line-justifier 28, 130 which extends beneath the transverse strip 29 of the table, under the plate 23. Upon its end is formed or mounted a stop-lug 30, which lies in an open space 31 between the

rear edge of the plate 23 and a thimble 32. The pusher and justifier is connected to an actuating-bar 33, which is in line with the pusher, its end passing beneath the thimbles 32 and projecting beyond the adjacent edge of the table. Its end is provided with a pin or lug 34, against which the free end of a leaf-spring 35, Fig. 3, bears, its other end being attached to the table, whereby the pusher is normally drawn back to remove its forward end from the chamber 17 or so nearly so as to permit the matrix to pass down under the impulse of the belts 8 and 9. The pusher is reciprocated rapidly, being moved in one direction by the spring 35 and in the other by a reciprocator-bar 36, Fig. 6, supported in a sleeve-bearing 37 and having a cross-head 38, within which is a race (shown in dotted lines in Figs. 4^a and 6) to receive a wrist or crank pin 39, carried by a rapidly-rotating disk 40, journaled upon any suitable support and driven by a belt from a gang-pulley 41, carried by a shaft 42, which is the power-shaft of the entire mechanism. The reciprocator-bar 36, Fig. 4^a, is provided with a head 43, which moves constantly in a line coincident, or substantially so, with the axial line of the pusher and justifier 28 when the table is at rest.

In order to bring one of the four pushers 28 in position to be operated by the reciprocator-bar 36 and at the same time bring the assembling-chamber in which said pusher operates into such position that it will receive the matrices in its entrance-opening 22, the shaft 16, carrying the table, is arranged to the left hand of the center of the machine, Fig. 1, and behind the magazine, Fig. 2, so that at each quarter-turn of the shaft 16 one of the assembling-chambers 17 shall be brought into substantial coincidence with the vertical plane in which the belts 8 and 9 travel, with the entrance-opening 22 beneath and in the same vertical plane with the tangent line of the two guide-rolls 14. The moment the quarter-revolution is accomplished and the parts referred to are brought into the positions described the shaft 16 is arrested and locked by automatic means, fully set forth hereinafter. It maintains this position until its movement is again initiated by the act of the operator by the means presently to be explained.

The matrices are, as already stated, released from the cells of the magazine by any known or preferred mechanism, a suitable escapement being provided to prevent the release of more than one matrix at the same moment. These devices do not necessarily form part of my present invention, and as they are well known to those skilled in the art, I have omitted them from the drawings and will give no further description of them.

With the matrices shown in Fig. 3^a I use the compressible elastic spaces shown, described, and claimed in the United States Letters Patent granted to me and to Lemon G. Hine, as assignee of an undivided half part of the right, title, and interest in said

Letters Patent, the same being dated the 8th day of March, 1892, No. 470,694. These spaces are handled precisely like the matrices and are stored in one of the cells of the magazine, or, if preferred, they may be placed in a separate but substantially similar cell should any large number be required. In Figs. 4^a, 5, and 7 I have shown these spaces, which are indicated by the numeral 44. They form no part of my present invention, save as they enter as elements in certain combinations of the mechanism by which they are handled. The spaces enter the assembling-chamber and leave it for distribution by the same entrance-openings 22, already described, and they are driven out through the same exits 22^a, provided for the matrices, which will be fully explained in their proper order, together with the devices co-operating with the distribution apparatus. I will only remark at this point that the matrices and spaces enter and leave the assembling-chamber at the same end thereof, the exit 22^a being adjacent to the entrance-opening 22 and separated therefrom by the two opposite lugs 27, Fig. 3.

Lying across the open top of the assembling-chamber is a cross-head 45, its ends resting and moving on the table. Attached to and dropping from this head to a point below the bottom of the assembling-chamber is a vertical follow-block 46, Fig. 4^a, having its flat face lying across the chamber 17. Connected to this follow-block and to the cross-head 45 is the extension-plate, forming part of a pusher 47, which lies in substantially the same plane as the bottom of the assembling-chamber 17 and between the lower face of the table and a keeper 48. The width of this pusher is such that it may move freely in the open bottom of the assembling-chamber, and its length is sufficient to enable the follow-block to slide from end to end of the chamber 17 without disengaging the plate 47 from the keeper 48. When the line of matrices is distributed, means are provided, as will be fully explained in proper order, whereby a force is applied to the follow-block, whereby the rank of matrices is moved step by step as the individual matrices are driven out through the exit-opening 22^a to the rear of the assembling-chamber to bring the matrices to a point where the ejecting devices may engage them in succession. When the entire line is removed, the vertical follow-block 46 is allowed to remain at the point reached by its last rearward movement, by which the last matrix in the line was brought in reach of the ejector, until the same assembling-chamber again comes into co-operative position with the matrix-assembling devices. The moment this position is reached the reciprocator-bar 36 engages the end of the pusher and line-justifier 28 and drives the follow-block 46 forward until it stands at substantially the point occupied by the matrix last inserted in the rank of matrices.

The speed of the belts 8 and 9 is designed to snap or force the matrices into the assembling space or chamber with such rapidity that ordinarily the pusher 28 will not strike a matrix before the latter fully enters the assembling space or chamber and is in position to be advanced by the pusher. As the matrices are carried down by the belts 8 and 9 and as their lower ends enter the opening 22, they may, in some instances, encounter the pusher 28 and rest an instant upon the upper side thereof. This will momentarily arrest the movement of the matrix and the belts 8 and 9 will slip thereon, until the retraction 15 of the pusher withdraws it from beneath the matrix, which instantly snaps downward into the assembling-space, its limit of movement being reached before the pusher can complete its retractile movement and again be projected or moved forward far enough to again encounter the matrix. The said forward movement of the pusher 28 will therefore cause its end to engage the flat vertical face of the matrix and push it against the follow-block 46, and thereby remove it from the entrance-opening 22 and out of the path of the matrix about to enter the same. Thus at each entrance of a matrix or space the follow-block 46 is advanced a step, together with the matrices which have been previously inserted. When the line is completed, the follow-block will be arrested by the closed end of the assembling-chamber, as seen in Fig. 5, and the operator must cease operating the keys of the keyboard. If, however, an oversupply of matrices should enter the assembling-space, the belt driving the actuating-bar 33 will slip and thus avoid damage to the parts. Any other suitable means, however, may be employed to 40 accomplish this result.

The operator will be guided in closing the line by his knowledge of the words to be printed, whereby he is enabled to slightly modify his spaces by increasing or diminishing them in the last portion of the line. As the elastic yield of the spacers under compression of the line will allow a margin of at least two letter-spaces or less, it will be seen that the ending of the line, the division of a 45 terminal word, or other expedients necessary to secure a correct and fair-appearing letter-press will cause no impediment to the rapidity of the work or become a source of error, as the elastic yield of the spaces will allow a 50 margin for correction of all mistakes in judgment, save those of the grossest character. The matrices having been assembled in sufficient number to complete the line, and the length of the latter having been determined 55 by the compression effected by the pusher and justifier-bar 28, the operator who is at the keyboard 49, Figs. 1 and 2, directly in front of the magazine initiates the movement of the machine-table 15 by means of a foot-lever 50, Fig. 2, having its fulcrum upon an upright bracket 51. This lever throws the clutch by which the shaft 16, Fig. 6, is so con-

nected with the power-shaft 42 that revolution is imparted from the latter to the former. I shall explain hereinafter the construction and 70 operation of these parts, my present purpose being to follow the operation of the machine in the handling of the matrices and to confine this part of the description closely thereto, reserving the power mechanism and the 75 devices for starting, automatically stopping, operating the mold, and so placing the crucible as to throw the melted metal into the mold for a further part of this specification. The shaft 16 therefore being set in motion 80 by the operator, who has filled the assembling chamber or space next to and parallel with the front of the machine, said revolution continues until the square machine-table 15 has advanced in the direction of the arrow in 85 Fig. 3 one-quarter of a revolution, whereby the assembling-chamber which has been filled with a line of matrices, in the manner described, is brought into a position at right angles with that occupied while the line was 90 set up.

For the sake of the description I have in Fig. 3 denoted the successive positions of the same assembling-chamber in the table by the letters *a b c d*, the letter *a* signifying the position of the chamber during the process of assembling or setting the matrices, *b* denoting the position of the same chamber after the table has made the first quarter-turn, bringing the said assembling-chamber to its second position, where it lies at right angles to position *a* and is brought into position to be locked up in the mold to cast the type-line. Position *c* is that assumed by the same assembling-chamber after the table has completed its second quarter-turn, bringing the said assembling-chamber into its third position, where it is parallel with position *a*, but separated from the latter by the breadth of the table. Here the matrices presented to the distribution apparatus are rapidly driven out of the assembly-chamber in succession and returned to the magazine to be used in some future assembling process. Position *d*, which is the fourth place assumed by the 100 said assembling-chamber, may be termed the "idler-place," as the emptied assembling-chamber, which has in the preceding or third place *c* been emptied of its line of matrices, is put to no use while it lies in position *d*. 105 This fourth place may be considered unnecessary, save as it is the result of the quadrilateral table. As the latter has four sides, it must have four assembling-chambers, in order that at each rotary movement an empty 110 assembling-chamber shall reach position *a* to enable the operator to assemble a second or third or fourth series of matrices, &c., this operation being performed while the operation at positions *a* and *c* are carried on automatically in the same period of time as the two operations taking place in positions *a* and *c*. 115

It will be seen from Figs. 1, 2, and 3 that

at each quarter-turn of the machine-table an empty assembling-chamber is brought from the fourth position *d* back to the first position *a* for a repetition of the first step, which 5 consists in assembling the required matrices in said chamber for the formation of the next succeeding type-line. It should be remembered, however, that the quarter-turn of the table which takes the assembling-chamber 10 from position *a* to position *b* also brings an empty assembling-chamber to position *a* to be filled with a line of matrices, while the type-line is cast at position *b*. Thus at each quarter-revolution of the table a line of matrices 15 is set up, a type-line is cast, and a line of matrices is distributed, the entire series of operations being carried on simultaneously at the points *a b c*.

It should be noted as an important feature 20 of my invention that when a line of matrices is once set up it is not removed from or moved in the assembling-chamber until the line is distributed. The matrices are justified, the type-line is cast, and the line of matrices is 25 removed to position *c* by the fractional revolution of the table 15. By this method I am able to simplify the machine and reduce the number of mechanical elements in a marked degree. The assembling-space beneath the 30 guide-rolls 14 being filled in the manner described, the operator presses the lever 50 with his foot and throws the clutches by which the table is turned a quarter of a revolution, whereby the filled assembling-space is brought 35 into position *b*, Fig. 3, where the line is cast.

The casting mechanism consists of a mold having jaws which open and close in the manner to be explained and with which the line of matrices is locked up to form what is 40 usually termed the "bottom" of the mold.

Referring to Fig. 6 it will be seen that in order to allow the table 15 to make its quarter-turn it will be necessary for the mold to withdraw somewhat to avoid collision between it and the angle of the table. For this purpose the crucible 53 is mounted in such manner that it may have a limited motion upon its support, as hereinafter explained, and the mold is detachably connected to its 45 spouts and moves with it. This movement is produced in one direction by a weight 54 and chain 55 and in the other by a cam-plate 55' on a shaft 56, having bearing on the pedestal for the crucible and on the main frame and 50 having a bevel-gear 56', driven by a like gear on the upper end of the shaft 16, Fig. 6. The face of the cam rests on an antifriction-roll 55 57 on the rear face of the crucible.

A spout 58 forms part of the crucible 53 and 60 rises from its bottom to a point in the plane of the table 15, its discharge end being directed outward. Upon this spout is mounted the mold, consisting of jaws 59, (Sheet 7 of the drawings,) having upon their ends jaw-levers 65 60, which are connected pivotally at the ends next the crucible, the lower jaw-levers having vertical lugs 61, to which the upper levers

are pivoted, Figs. 7 to 10. Upon said lugs 61 are formed outwardly-projecting pins 62, which lie in channels 63 in rigid supporting-brackets 64, Fig. 13, next the outer faces of the lever-arms. In the vertical faces of these brackets are formed diverging channels 65, which receive pins or lugs 66 on the lever-arms, causing the latter to spread or approach 75 each other and open or close the mold-jaws 59.

Where a polygonal or rectangular table is used, the latter being of the form shown in the present case, a movement of the mold is necessary at each quarter-turn of the table to 80 enable the angles of the latter to pass the mold and bring the matrix-assembling space next in succession in position to form part thereof. To enable this to be accomplished, the crucible is also rendered movable, and 85 this movement is made available for the production of the necessary action of the jaws 59 in the following manner: The crucible is mounted upon cross-heads 67, Figs. 6 and 15, supported upon an arched pedestal 68 90 and having in their inner faces ways or grooves 69, in which lie and move parallel bars 70 upon the opposite sides of the crucible. This construction gives a horizontal movement and retains the crucible at each 95 point thereof in the proper position relative to the table. Normally the crucible and mold will at all times lie at the utmost distance possible from the table, this being due to the effect of the weight and chain 54 55; but its 100 movement being checked by one part of the scroll-cam 55' it will by the opposite part of the latter be driven up toward the table until the lips 71 on the mold-jaws enter the lateral casting-opening 72 in the vertical edge of the 105 table 15, Figs. 6 and 10, through which the edges of the assembled matrices are exposed. With these edges the lips may contact, the nibs of the spacers passing between said lips and making close joints therewith. The machine-table is moved through a quarter-turn by the shaft 16, Fig. 6, as already set forth, to which revolution is given by the worm-gear 73 on said shaft meshing with the worm 41 on the power-shaft 42, the operation being 110 initiated by the operator by means of a lever 50, Fig. 2, already mentioned. As the table finishes the required movement, the rotation of the shaft is checked by means shortly to be explained, and the table is held motionless during the operation of casting. The 115 first thing to be done after this movement is to rectify the matrix edges, which is done by the pusher and line-justifier 28, Fig. 5, the bar 33 thereon being engaged by an automatic driving-arm 74, rigidly mounted upon the axis or fulcrum 75 of a lever-arm 76, said fulcrum 75 being mounted on the upper part of the bracket 51, Fig. 23. Upon the axis or fulcrum 75 is mounted an arm 77, Fig. 5, 120 dropping from the axis to a point where a pin 78, Fig. 25, extending from its lower end may enter a slot in a wall 79, which forms part of a housing inclosing a slide-block.

80, to which said pin is rigidly connected. The slide-block is moved in the housing by means of a cam 183 on the shaft 16, forming one of a series of cams, described hereinafter. By this movement the end of the driver 74 is caused to swing toward and engage with the end of the bar 33, Fig. 5, the action of the cam being such as to drive the matrices together and compress the line to its exact length. At the same time an aligning-head 81, Figs. 5, 6, and 40, supported by spring-raised arms 82, is brought by means of a cam 83 on the shaft 56 down upon the ends of the matrices and spacers as they project above the table. The cam 83 engages an antifriction-roll 84 on the lining-head 81, and by the action of the latter and of the pusher the line of matrices is brought into position for casting. The cam 183, Fig. 23, operating the arm 77, acts upon a roll 85, Fig. 5, journaled on the slide-block 80, and its return movement is effected by a spring 86, Fig. 25, connected to the arm 76 and to a pin 87 on the bracket 51. This spring withdraws the driver 74, Fig. 23, when the slide-block is released by the cam operating it. The parts being in this position, the crucible moves toward the table under the impulse of the cam 55', Fig. 6, and as it moves up the mold-jaws 59, Figs. 11, 12, and 13, are brought together by means of the pins 66, sliding in the cam grooves or races 65, until the moment when the lips of the mold are brought under the cam-pressure against the rectified and justified matrices. At this moment a scroll-cam 86, Figs. 6 and 15, releases an arm 87, having a friction-roll 89, which rides on the flange 90 of the cam, and thereby drops the plunger 91, which forms part of the piston 92 of the crucible. This piston works in a pump-cylinder 93, which communicates with the spout 58 of the crucible. The weight of the parts being properly adjusted, this drop splashes the melted metal through the spout into the mold with a sudden rush and with such force as to fully fill the mold in an instant and before the metal first entering has time to chill. As the plunger reaches its lower limit of movement, a severing-knife 94, arranged in the upper mold-jaw, Figs. 6, 9, and 10, as near as may be to the point where the spout joins the mold, is driven down by a cam 95 on the shaft 56, severing the metal in the mold from that outside and accurately trimming that edge of the type-bar which is parallel with the type-face. At the same time the scroll-cam 86, Fig. 15, re-engages the arm 87 and lifts the plunger, by which action the fluid or semi-fluid metal remaining in the spout behind the knife 94 is sucked and partly drawn by gravity back into the crucible. During this operation the operator has been setting up another line of matrices in a second assembling-space, and upon completion the lever 50 is again operated, the crucible is drawn back, and the jaws of the mold are opened, exposing the type-bar 97, Fig. 14, upon which are formed longitudinal parallel ribs or pro-

jections 98, one lying at or near the base of the type-bar and the other at or near the other edge or type-face.

70.

The percentage of error in casting where those vertical faces of the type-bars which must have exact lineal accuracy are of limited area will be much less than when they are of large area. In other words, the contacting-faces of the narrow ribs will be true in nearly every instance and will require no dressing, whereas it might well be that several per cent. of the plain-surfaced type-bars would present burrs on the edges or other defects requiring trimming before they could be locked up in the form.

75.

A cross-head 99, Fig. 15, is mounted on the upper end of the plunger 91 to arrest its downward movement and avoid shock against the bottom of the crucible by means of opposite bracket-arms 100 on the opposite parts of the arched pedestal. In order to lift the plunger to the proper height before the crucible is again moved to permit a new adjustment of the table, the cam 55', Fig. 6, is formed with riding faces 101, by which the crucible and mold are held in locked position until the shaft 56 has so far revolved as to carry the cams off the lining-head 81 and knife 94. As the table 15 makes its first rotary movement, the line of matrices which has been set up in the assembling-space while the latter stood in position *a*, Fig. 3, is advanced a quarter-turn and brought into position *b*, where the cast is made, 100 as already explained. As the table 15 makes its second rotary movement, the same line of matrices will be brought around to position *c* for distribution. As this second rotary movement is initiated, the slide-block 80, Figs. 23 and 25, is released by the means hereinafter explained and the driver 74 withdraws from the bar 33 of the pusher and justifier, and as the movement is completed the line of matrices from which the cast has been made is 110 placed in proper relative position to the distribution mechanism, Fig. 7.

95.

I take the matrices out of the assembling-space 17 at the same end thereof at which they enter, and in order to do so they must 115 be driven from the other end of the space as fast as they are removed from the exit end. For this purpose I provide a driving-arm 102, Figs. 2, 6, 7, 8, 8^a, and 23, mounted on a guide-bar 103, which has its ends supported in short 120 posts 104, 104', which rise from a shelf 105, Figs. 2 and 3, forming part of a sleeve 106, which surrounds the tubular shaft carrying the table. The driving-arm 102, Figs. 7 and 8, is acted upon by a spring 107, coiled on the 125 guide-bar, by which said driving-arm is forced toward that end of said guide-bar 103 which lies directly under the exit end of the matrix-space in the table when the latter has finished its second rotary movement, at which time the 130 guide-bar lies beneath and in parallelism with the matrix-space above, the post 104^a being beneath the exit end of said space. On this post 104^a, Figs. 7 and 23, is journaled a short

shaft having on one end a belt-pulley 108 and on the other end a wheel 109, having a crank-pin 110. This crank-pin engages a race 112 in a cross-head forming part of a vertical reciprocator 113, which is guided in a channel in a short projection from the post 104^a. The belt-pulley is driven by a belt 114 from a driving-pulley on the power-shaft 42, Fig. 6. This mechanism gives a continuous reciprocation to the part 113, whereby when the table has completed its second movement the enlarged head of the reciprocator will make engagement with the ejector 115, Fig. 7, which lies in a drop-bracket 116 on the lower side of the table. The ejector consists of a bar 115, moving vertically in a keeper 117, its end entering the matrix-space in the table at a point beneath the exit-opening 22^a and having mounted thereon an ejecting-head 118, which plays up and down in line with the exit-opening 22^a, Fig. 26, at such a point that it will engage the lower extremities of the matrices singly and drive them one at a time upward, the side lips on each passing between the lugs 27 and the lips 26, Fig. 3, which give space for the passage of said lips, the thicker body of the matrix being provided for by a slight extension of the opening in the direction of the pusher 28, as shown at 119 in Fig. 26. As the matrices pass beneath the lugs 27 as they are driven toward and into the exit-opening 22^a, the construction described affords a gage whereby the passage of more than one matrix at the same moment is prevented. The function of the shoulders 26 is substantially that of a gage, since in connection with the transverse lugs 27 the parts of the exit-opening 22^a, through which the side lips of the matrix must pass, are limited to the thickness of said lips, so that only a single matrix can possibly be ejected at each action of the ejector 115.

The ejector 115, Figs. 26 and 27, is provided with a rack 120, with which a pinion 121 meshes, the shaft of said pinion having a coiled spring 122, Fig. 27, by which it is normally turned in such direction that the ejector is at all times thrown down or withdrawn from the opening 22^a.

As the table 15 makes each turn or rotary movement it is evident that provision must be made whereby the downwardly-extending ejector 115 may pass the driving-arm 102 without interference therewith, and whereby the latter shall be caused to make the proper engagement with the depending end of the follow-block in the next matrix-assembling space. In other words, as the table 15 makes its second rotary movement to bring the line of matrices from position *b* to position *c* for distribution the depending end 46 of the follow-block, Figs. 7 and 8^a, must engage the end of the driving-arm 102 and carry the same along with it until the movement of the table ceases. This action forces the driving-arm 102 along the guide-bar 103, compressing the spring 107 and exerting upon the line of

matrices a force which tends to drive them toward the exit end of the space in the table in which they lie. As each matrix is successively driven out of said space by the ejector 115, those remaining in line are moved up by the push of the driving-arm 102, which in this manner gradually approaches the exit end of the assembling-space in the table. After bringing the last matrix to the ejector 115 it is evident that in order to give the next advance or the third rotary movement to the table this driving-arm 102 must be gotten out of the way of both the depending end 46 of the follow-block, and the downwardly extending ejector 115. For this purpose I provide the driving-arm 102 with a laterally-extending foot-piece 123, Figs. 8 and 8^a, having a downwardly-curved end which overhangs a horizontal flange 124, which is supported upon the posts 104 104^a. Beneath this flange is arranged a horizontal pivotal axis 125, upon which is mounted the larger end of a curved riding plate 126, normally held by a spring 127 with its concave face against the edge of the flange 124, in which position its free longer edge, parallel with the pivotally-mounted edge, will present a horizontal surface 128, lying a little above and parallel with the flange 124. This surface is terminated at such a point adjacent to the post 104^a that the foot-piece 123 will pass off the same and drop upon the end of the flange 124 at the same instant that the movement of the driving-arm 102 in the direction of the arrow in Fig. 7 is arrested by the post 104^a. Thus at the same instant that the last matrix in the line is carried into the exit-opening the driving-arm producing such movement is snapped into the position shown in dotted lines in Fig. 8^a. This action of the driving-arm is produced by the spring 107, which is positively fastened to the guide-bar 103 at one end and to the driving-arm 102 at the other end, whereby it may have a torsional force which will snap the end of the foot-piece 123 downward as it rides off the horizontal face 128. This force in no respect impairs the action of the spring 107 in pushing the matrices to the end of the space in which they stand. In this position, as shown in Fig. 8^a by dotted lines, the driving-arm 102 will be engaged by the depending end of the follow-block 46 as the table turns, this engagement being indicated in Fig. 8^a by the dotted lines, which show the edge and face of the follow-block as it swings in the arc of a circle, the figure referred to showing its position just as engagement is made. Said figure being an end elevation of Fig. 8, looking toward the right hand, it will readily be seen that when the table has completed its movement not only will the follow-block have been swung into the same vertical plane with the axis 108, where it will engage the driving-arm 102 when upright, as shown in full lines in Fig. 8^a; but by reason of the fact that the curved path of the depending follow-block as it moves with the rotating ta

ble carries it toward and then into the vertical plane of the axis 108 its foot-piece 123 will be lifted from the flange 124 and caused to rise, pushing the curved riding plate 126 outward against the resistance of the spring 127 until said foot-piece passes above the free edge of said riding plate, which at once snaps underneath it. This takes place between the point where the follow-block engages the driver-arm and the point where the further movement of the parts is arrested by the completion of the movement of the table. The driver-arm will now be erect, its foot-piece resting and ready to ride upon the horizontal edge 128 of the riding plate, said driving-arm being retracted upon the guide-bar 103 and the spring 107 being placed under tension. At the same moment that this position is reached the reciprocator 113 engages the ejector 115 and the removal of the matrices begins, each matrix as it is driven out making room for the advancement of the line of matrices by the spring-pushed driving-arm 102. At each upward stroke of the ejector 25 the ejecting-head 118, which is slightly beveled on top to increase the security of its engagement, catches the lower end of the first matrix and carries it out, as seen in Fig. 7.

The lines of movement of the follow-blocks 30 46 and driving-arm 102 are rendered clear by the diagram Fig. 41. When the assembling-chamber is filled with matrices, the follow-block will move in the arc indicated by the line α' and strike the driving-wheel 102; but when 35 the matrices have all been ejected from the assembling-chamber the follow-block of such chambers will occupy the position indicated by dotted lines, Fig. 46, and consequently clear the driving-arm 102, and on the next movement of 40 the table will travel in the arc indicated by the line α^2 . This result is due to the fact that when the follow-block has reached the end 45 of the assembling-space after the matrices have all been removed such follow-block lies at a greater radial distance from the center of the table than when it stood at the other end of the assembling-space with a line of matrices in front of it.

Immediately above the table 15 and over 50 the exit-opening 22^a of the matrix-assembling-space when the latter occupies the position it assumes after the second movement of the table (shown by the letter c in Fig. 3) are journaled rolls 129 and 130, Figs. 1 and 2, of 55 small diameter, their peripheries being quite close to the surface of the table. Over these rolls is carried a belt 131, parts of which are normally in contact and run in unison, their direction of movement being upward or away 60 from the table. The tangent line between the said contacting portions of this belt is arranged to come over or substantially over the exit-opening 22^a in the matrix-assembling space in the table, Figs. 1, 2, and 7, so that 65 the matrices as they emerge from said space shall enter between the belts and be grasped thereby, so that they may travel with said

belt, one of the rolls—viz., that numbered 130—being mounted upon a journal which lies in a movable yoke 131', lying in a bracket 132 70 and pressed by a spring 133 toward the other roll, thereby holding the outer faces of the belt in contact. By making the roll 129 immovable the line of movement of the matrix may be caused to be in the plane of the face 75 of the next matrix against which it lies.

The belt 131 extends upward to the upper part of the machine, preferably upon one side of the magazine, where the belt is so disposed as to deliver the matrix lying between the 80 contacting-surfaces of the belt to a suitable mechanism for distributing the matrices or returning them to the cell in the magazine from which they were taken. In the present instance I have shown a known form of this 85 mechanism with a few changes and with some additional features to adapt the same to the needs of my invention.

The carrying-belt 131 is carried over independent rolls 132', Fig. 17, at the top of the 90 machine, one of said rolls being lower than the other to provide a space for the horizontal movement of the matrix as it passes upon the end of the distribution-bar. The latter is a bar 133', having a suitable series of ribs and 95 grooves on its two converging sides to engage the combination notches and points in the end of the matrix. It lies over the open ends of the cells of the magazine and deposits the matrices therein in the well-known manner. Its end 133^a, lying adjacent to the belt 131, is plain-surfaced, being formed like the remaining portion in shape, but without ribs or grooves. The distribution-bar is so arranged that the end receiving the matrices 105 lies substantially in a vertical plane coincident with the contacting portions of the belts 131, as seen in Fig. 17.

The pulleys 132' are journaled on suitable axes, and one of the latter is mounted in a 110 frame 134, Fig. 17, rigidly attached to the machine-frame, while the other or higher pulley has its journals mounted in elastic arms 135, rising from a bracket 136, Fig. 1.

The frame 134 consists, essentially, of a vertical plate transverse to the distribution-bar and extending below the same to afford support to brackets 134^a of any suitable shape, such as those shown in Figs. 17 and 18. A second and parallel plate 134^b is used to afford 120 a rigid support for the brackets 134^a, both of said plates being sustained by the distribution-bar or by the upper part of the framework of the machine.

In the face-plate of the frame 134 is formed 125 a cruciform opening 137, Figs. 18 and 39, which extends some little distance below the distribution-bar 133' and is provided with guards 138, projecting from its sides and having such form and arrangement that they 130 will afford supports to the matrices as the latter pass out of the grasp of the belt 131, but preventing them from passing upon the distribution-bar until these guards shall pass

through the side spaces on the matrix between the lips 19 and 20, as seen in Fig. 3^a. One of the guards 138 has its middle portion removed to form a space for the passage of the lips upon the spaces, as said lips project from one of the longer sides of each space. This construction of the guard is shown at the right hand of Figs. 18 and 39. When the matrix rises far enough to bring its upper end upon the guards 138, it will rest and move thereon until it passes the pulleys 132', the higher pulley moving slightly away from the end of the bar as the matrix passes, but immediately pressing forward after it has passed, and by said movement pushing its notched end upon the plain-surfaced end 133^a, Figs. 18 and 19, of the distribution-bar 133'. The movement of the upper pulley away from the bar is produced by its yielding to the passage of the matrix and is permitted by the elasticity of the arms 135, which support said pulley and move it back toward the end of the distribution-bar after the matrix has passed. The lower pulley 132' is not movable, its journal-supports being rigid. Here it is engaged by a V-shaped traveler 140, which connects two belts 141, Fig. 19, driven continuously by pulleys 142, Fig. 1. These travelers are mounted on the belt at regular intervals and move just beneath the distribution-bar, to which they closely conform in shape, each having arms 144, Fig. 8, which extend laterally from the upper end of the V-shaped arms.

Upon one side of the frame 134, Fig. 17, is pivotally mounted a guard 145, Fig. 39, its axis being provided with a spring 146, Fig. 19, by which it is thrown toward the distribution-bar in order to bring a head 147, Figs. 18, 21, and 39, on its vibrating end into the path of one of the lips 20 on the matrix just as it is about to pass upon the distribution-bar, thereby stopping the further ascent of the matrix, which obviously prevents upward movement of the entire series of matrices between the belts, as they lie one below another in the same vertical plane. The upper end of the guard is beveled at 149, as seen at Figs. 19 and 39, at a point above the head 147, and with this bevel 149 the beveled ends 150 of the travelers 140, Fig. 20, successively engage, pressing the head back and drawing it out of the path of the matrix. It will be seen that as the latter passes on the bar 133' another matrix cannot be placed thereon until a second traveler 140 comes to the point where it can operate the guard, because the latter holds back the column or series of matrices until a traveler 140 acts on the guard to release the uppermost matrix, so that it can rise. By this means the matrices will be equally spaced on the distribution-bar. Should the matrices for any reason be shorter than those in use, the rolls 129 130 may be provided, Fig. 16, with an auxiliary take-up roll 153, journaled in arms 154 and revolving opposite a friction-block 155. The auxiliary roll being small, it can be arranged partly in the exit-opening,

while the friction-block can be brought down close to the block 23. The roll 153 will preferably be rotated by surface contact with the belt passing over the rolls 129 or 130.

As the matrices when placed in the assembling-space have their edges all turned toward the front, said edges will when the said assembling-space reaches position c, Fig. 3, be turned in the opposite direction, and being taken out for distribution they would enter the magazine turned half-way round. To rectify this, I impart to the flexible carrier or belt 131 a half-twist, as seen in Figs. 1, 2, 80 and 22. The belt is carried over and between pulleys 154, of larger size, separated from contact to enable the matrices to pass without strain due to the too sharp curvature of the belt. The return or downward traveling portions of the belt are carried under small rolls 155.

In order to insure the proper frictional grasp of the matrices by the flexible carrier or belt, they may be inclosed in a frame between a plate 156 22^a 22^b 22^c and leaf-springs 157, mounted on bridge-pieces 158, connected to the plate 156 by posts 159. Guide-ribs 160 may be formed upon the plate 156, if desired, between which the belt may travel. 95

The table is moved by operating the pedal 50, Figs. 23 and 24, which has a forked end provided with slots which engage pins set in the edge of a disk 161, Figs. 6 and 38, loose upon a sleeve 162, which surrounds the lower part of the shaft 16. Loose with this sleeve, which carries the worm-gear 73, is a clutch-disk 163, having opposite clutch-plates 164, which pass up through the body of the worm-gear, their ends lying when disengaged just below the 105 crown-teeth of a clutch-disk 164^a. This clutch-disk forms part of a sleeve 165 intermediate between the sleeve 162 and a sleeve 166, carrying the table 15. 100

Upon the intermediate sleeve 165 is rigidly mounted a disk 167, connected by bolts 168 with a cam-disk 169, loose on the lower end of the sleeve 166. In the cam-disk 167 is formed, Figs. 33 and 34, an aperture or opening 170 for a vertical locking-plate 171, Fig. 6, normally depressed by a spring 172, (see Fig. 6,) but capable of riding by its lower end upon an inclined semi-annular plate 173, Figs. 6 and 24, until it is raised sufficiently to pass entirely through the aperture 170 in the cam-disk 167 115 and engage a cam-disk 175, rigid on the sleeve 166. This engagement takes place as the locking-plate reaches the highest point on the incline, which occupies one-quarter of a turn, while the engagement of the locking-plate 120 with the cam-disk 175 continues during a second quarter-turn, as will appear from Fig. 24. The purpose of this construction is to enable the operator to initiate the action of the mechanism by depressing the pedal 50. By the 130 movement of the shaft 16 a latch-bar 176, Figs. 6, 28, and 30, is caused to withdraw its detent end 177 from a notch 178, Fig. 28, of the disk 175, which I term the "index-disk." Upon the

end of the latch-bar 176 is a vertical stud, on which is a roll 179, lying below the latch-bar, but having its periphery projecting slightly beyond its end, Fig. 30. This roll lies in a 5 chamber 180, Fig. 6, in the machine-frame and engages the peripheral face of the cam-disk 169, which I term the "latch-cam." (See Fig. 33.) As the latch-cam 169 begins to move before the locking-plate 171 engages the index-cam 175, and as this engagement does not 10 take place until the beginning of the second quarter-turn of the shaft, the latch-bar will be driven out of engagement with the notch 178 of the index-cam by its roll 179, which rests 15 upon the edge of the latch-cam 169. After making the first quarter-turn, during which it travels upon the edge of the latch-cam, it rides upon the cam-face 184, Fig. 35, thereby drawing the latch and releasing the index-disk. After less than the second quarter-turn is completed it again falls upon the riding edge of the latch-cam and brings the 20 detent end 177 of the latch-bar up against the edge of the index-disk, ready to make engagement with the approaching notch 178 of the 25 said disk. Four of these notches are made in said disk at equal intervals and at such points as to arrest the table after each quarter-turn. If the table is of other than 30 rectangular form, the index-disk will correspond therewith and will have as many notches as there are sides.

Immediately below the cam-disk 167 lies the lock-up cam 183, Fig. 35, bolted to the 35 latch-cam 169 and the intermediate cam 167, and also connected by the locking-slide 171. This lock-up cam has a cam-face 184^a of about one-quarter its circumference, the remaining three-quarters of said circumference being 40 riding-face. Its function is to act upon the slide-block 80 at the proper moment to operate the drive-arm 74 and lock up the line, holding it under compression while the casting takes place. As the table only turns during 45 the second quarter-turn of the shaft 16, Fig. 24, it does not fully reach position *b*, Fig. 3, until the shaft 16 has completed half a revolution. The roll 80, therefore, will stand ninety degrees of arc in advance of the cam-face 184^a or at the point *d*, Fig. 35. The lock-up will continue during the third quarter-turn, or a little less than a full quarter-turn, and during this period the line of type is 50 cast. The remainder of the revolution of the shaft 16 is occupied in raising the pump-plunger, and at the same time operating the severing-knife and sucking the surplus metal back into the crucible, withdrawing the crucible and mold, opening the latter and removing the cast line of type.

I have described the belt mechanism for carrying the matrices from the rotating table or platform to the distributing mechanism as composed of a single belt or carrier so disposed and supported by pulleys as to provide two portions, which are normally in contact and run in the same direction; but I do not

confine myself to this particular construction and arrangement, as other forms of belt mechanism may be employed without affecting the 70 spirit of my invention.

What I claim is—

1. In a machine for casting lines of type, the combination, with a keyboard and magazine, of a machine table or platform having 75 a series of devices for receiving and retaining a line of matrices and means for giving said table an intermittent fractional revolution to advance the line set up to a second position and bring a succeeding matrix-receiving 80 device into position to receive a line of matrices while a further operation is carried out with the line previously set, substantially as described.

2. In a machine for casting lines of type, 85 the combination, with a magazine and suitable means for selecting and assembling a line of matrices, of a rotating machine table or platform provided with a plurality of matrix receiving and retaining devices and 90 means for rotating said table to bring the lines of matrices set up to a mold and then to distributing mechanism, substantially as described.

3. In a machine for casting lines of type, 95 the combination, with suitable means for selecting the matrices and for casting a type-line from the same when assembled, of a machine-table having a series of assembling 100 spaces or chambers arranged thereon and means for rotating the table to bring a line of matrices into position to co-operate with the casting mechanism and at the same time bring a succeeding assembling-chamber into 105 position to receive the matrices from the magazine, substantially as described.

4. The combination, with a magazine for containing matrices and spacers, of a series 110 of devices for obtaining matrices from the magazine-cells in any desired orderly arrangement, a table mounted on a central shaft and provided with a series of assembling chambers or devices, suitable casting devices arranged to co-operate with a line of matrices contained in a matrix-assembling space or 115 chamber, distributing mechanism so arranged as to operate upon a line of matrices in another space or chamber, and means for rotating the table to bring one empty matrix space or chamber into position to receive a line of 120 matrices and at the same time bring a second and third preceding chamber or device to the casting devices and to the distributing mechanism, respectively, substantially as described.

5. In a machine for casting lines of type, 125 the combination of a rotatable table or platform, with means for assembling matrices thereon, casting devices, and means for rotating the table, substantially as described.

6. In a machine for casting lines of type, 130 the combination of a support and a rotatable table arranged on the support and having a plurality of matrix-assembling spaces, with

means for assembling matrices in said spaces, casting devices, and means for rotating the table on the support, substantially as described.

7. In a machine for casting lines of type, 5 the combination of a square rotatable table having a matrix-assembling space at each side portion and devices for advancing and supporting the matrices in each space, with means for delivering the matrices into and 10 discharging them from the spaces, casting devices, and means for rotating the table, substantially as described.

8. In a machine of the kind specified, a revoluble machine table or platform of rectangular form, having upon each side a matrix-assembling space or chamber provided at one end with entrance and exit openings and a spring-retracted pusher and justifier and at the other end with a movable follow-block, 20 and having beneath the exit-opening of each space or chamber an ejector adapted to drive the matrices upward out of said space or chamber, substantially as described.

9. In a machine of the character specified, 25 a rotating machine table or platform mounted upon a central support and provided upon each side with a matrix-assembling space or chamber, having at one end transverse extensions, constituting matrix-entrance openings and exits, the latter having such size as 30 to permit the passage of lips on the edges of the matrices, and thereby constituting a gage to avoid the ejection of more than one matrix at the same moment, substantially as described.

35 10. In a machine of the kind described, the combination, with a magazine composed of individual cells having their exit ends arranged in two downwardly-converging lines 40 meeting at a central point, of matrix-carrying belts beneath said exit ends, a pulley upon which said belts are brought in contact, guide-rolls, one of which is yielding, between which the belts pass and beneath which 45 they separate, and a revoluble machine table or platform having a plurality of matrix-assembling spaces or chambers adapted to be brought by the partial revolution of the table beneath the said guide-rolls successively, substantially as described.

50 11. In a machine of the type set forth, the combination, with a magazine composed of individual cells, of belts and pulleys arranged to receive the matrices as they are obtained from the magazine, a pair of guide-rolls between which the belts pass and beneath which 55 they separate, a machine table or platform having a series of matrix-assembling spaces or chambers so arranged as to be brought successively beneath the guide-rolls by the partial revolution of the table, casting mechanism arranged to register with one of said assembling-spaces after each partial revolution, distributing devices so arranged as to register 60 simultaneously with another of said assembling-spaces, means for operating said cast-

ing mechanism and distributing devices automatically while the operator sets up a line of matrices by the selecting and assembling mechanism, and means for giving a partial 70 revolution to the machine-table, substantially as described.

75 12. In a machine of the type set forth, the combination, with a magazine for the matrices and spacers, of selecting and assembling mechanism to carry the matrices to the point where the line is formed, a machine-table having matrix-assembling spaces or chambers to receive the selected and assembled matrices, casting devices, a distribution-bar arranged 80 above the magazine-cells, and a belt mechanism engaging the matrices and carrying them successively to the distribution-bar, substantially as described.

85 13. In a machine of the type set forth, the combination, with a magazine and matrix selecting and assembling devices, of a machine-table having one or more matrix-assembling spaces or chambers, a distribution-bar, and a belt mechanism engaging the matrices 90 successively and carrying them upward to said distribution-bar, substantially as described.

95 14. In a machine of the type specified, the combination, with a magazine, of matrix-assembling mechanism, a machine-table having one or more matrix-assembling spaces or chambers, and a belt mechanism engaging the matrices as they are separately removed from the line and carrying them successively to the distributing mechanism, substantially as described.

100 15. In a machine of the type set forth, the combination, with a matrix-magazine, of a belt mechanism to carry the matrices from the line set up to the distributing apparatus, substantially as described.

105 16. In a machine of the type set forth, the combination, with a matrix-magazine and suitable distributing apparatus, of means for supporting the assembled line of matrices, 110 and a belt mechanism which receives the matrices successively and delivers them to the distributing apparatus, substantially as described.

115 17. In a machine for casting lines of type, the combination, with a magazine and suitable selecting and assembling devices, of a table having matrix-assembling spaces or chambers arranged at intervals thereon, means for rotating said table, a casting mechanism with which one of said assembling-spaces is caused to register by means of said 120 rotary movement, a distribution apparatus with which a preceding and separate space is caused to register, a belt mechanism having 125 continuous movement to convey the matrices to the distribution apparatus, an ejector to drive the matrices out of the assembling-space, and automatic means for operating the casting and distributing mechanism, substantially as described.

130 18. In a machine for casting lines of type,

the combination, with a machine-table having one or more spaces or chambers in which the matrices are assembled, of ejectors to drive the matrices out of said chamber, a belt receiving the ejected matrices and carrying them to the distributing apparatus, and two pulleys arranged at different points, one being elastically movable beneath the end of the distribution-bar, said pulleys carrying the belt by which the matrices are removed from the assembling-spaces to the distributing devices, substantially as described.

19. In a machine for casting lines of type, the combination, with an intermittently-rotating table having a plurality of assembling-spaces or selected matrices, assembling devices to carry said matrices to the space where they are set up, a distributing mechanism, a continuously-moving belt by which the matrices are carried to the distribution mechanism, and pulleys driving said belt and having their axes of revolution parallel with each other, a half-twist being given to the belt, substantially as described.

25. 20. In a machine for casting lines of type, the combination, with a machine-table having a series of assembling-spaces, of a matrix-magazine, a casting mechanism, a distribution apparatus, a belt mechanism between the same and the machine-table, an ejector for driving the separate matrices out of the assembling-space, and means for rotating the table and reciprocating the ejector, substantially as described.

35. 21. In a machine for casting lines of type, the combination, with a rectangular machine-table having a plurality of spaces for assembling the matrices, of an assembling mechanism, means for giving a quarter-turn to the machine-table at intervals, a casting mechanism arranged to register with the line of matrices after the first quarter-turn, means for moving the crucible to avoid the angles of the table and to lock up the matrices in the mold, a distributing apparatus with which the same line registers after the second quarter-turn of the table, and a belt mechanism which conveys the matrices from the machine-table to the distribution-bar, substantially as described.

50. 22. In a machine for casting lines of type, the combination, with a table having an assembling space or chamber for a line of matrices, of a mold having jaws which open upon a pivotal connection in such manner as to separate the interior faces of the jaws one from another, one of said faces being provided with intaglios for the formation of longitudinal ribs or raised surfaces in low relief projecting from one face of each line when cast, substantially as described.

23. In a machine for casting lines of type, a mold composed of two jaws connected by a pivotal joint to enable said jaws to separate from each other in opening and approach in closing, one of said jaws being provided with intaglios for the formation of longitudinal

ribs or raised surfaces in low relief upon one face of the cast line, substantially as described.

24. In a machine for casting lines of type, the combination, with a table having assembling-spaces for the assembled matrices, of a follow-block arranged in one end of said space, a force with which said follow-block is brought in contact as the table turns, means for rotating said table at intervals to advance the line to a distribution mechanism, a pusher at the other end, of the assembling-space to advance the assembling matrices as they enter and push them against the follow-block, which forms a support for the end of the line, a reciprocation-bar, and means for operating the same, substantially as described.

25. The combination of a rotatable table, means for assembling matrices thereon, casting devices, means for rotating the table, and mechanism for taking the matrices from the table and distributing the same, substantially as described.

26. The combination, with a table or platform, means for assembling matrices thereon, casting apparatus, and distributing devices, of belt mechanism for taking the matrices from the table or platform and delivering them to the distributing devices, substantially as described.

27. The combination, with a magazine for the matrices and spacers and with an assembling chamber or space, of a pair of coacting belts arranged beneath the two inclining series of exit ends of the cells of the magazine, and an elastic plate hanging from a support at or near the point where the two inclining series of exit ends meet, substantially as described.

28. The combination, with a magazine, a machine-table, and means for selecting and obtaining matrices and spacers from the cells of the magazine, of a casting mechanism, a distributing mechanism having a distribution-bar, a belt receiving the matrices and spacers from the machine-table and carrying them to the distributing mechanism, and a pair of rolls adjacent to the end of the distribution-bar, over which the belt runs, one of said rolls being above the other and mounted on a journal-support, which is pressed toward the other roll and the end of the distribution-bar, whereby the matrices and spacers are allowed to pass and are automatically placed upon the end of the distribution-bar, substantially as described.

29. The combination, with a distribution-bar and with a flexible belt carrying the matrices and spacers thereto, of a pair of rolls adjacent to the end of the bar to carry the belt, one roll being elevated above the other and having a spring-support adapting it to yield in a direction away from the end of the bar, a pivoted spring-actuated guard mounted on a frame having a matrix-opening into which the end of the guard normally projects, and

a series of travelers carried by duplex belts in parallelism with the distribution-bar, the beveled ends of said travelers being adapted to engage the beveled end of the guard and 5 retract it to allow passage for a matrix or spacer, substantially as described.

In testimony whereof I have hereunto set

my hand and affixed my seal in presence of two subscribing witnesses.
